UNITED STATES PATENT OFFICE.

JOHN H. GOSS, OF WATERBURY, CONNECTICUT, ASSIGNOR TO SCOVILL MANUFACTURING COMPANY, OF WATERBURY, CONNECTICUT, A CORPORATION OF CONNECTICUT.

DESIGN FOR A TOP FOR POWDER-RECEP'TACLES.

No. 38,305.

Specification for Design.

Patented Nov. 6, 1906.

Application filed July 26, 1906. Serial No. 327,968. Term of patent 14 years.

To all whom it may concern:

Be it known that I, JOHN H. Goss, a citizen of the United States, residing at Waterbury, in the county of New Haven and State of Connecticut, have invented a new, original, and ornamental Design for Tops for Powder-Receptacles, of which the following is a specification, reference being had to the accompanying drawings, forming part thereof.

Figure 1 is a front elevation. Fig. 2 is a

rear elevation; and Fig. 3 is an elevation between these two views, showing my new design.

I claim—

The ornamental design for a top for powder-receptacles, as shown.

JOHN H. GOSS.

Witnesses:

M. L. SPERRY,
F. J. GORSE.

It is hereby certified that in Letters Patent No. 38,305, granted November 6, 1906, upon the application of John H. Goss, of Waterbury, Connecticut, for a Design for a "Top for Powder-Receptacles," an error appears in the printed specification requiring correction, as follows: The following sentence, constituting lines 10-13, inclusive, to wit: "Figure 1 is a front elevation. Fig. 2 is a rear elevation; and Fig. 3 is an elevation between these two views, showing my new design," should be stricken out and the sentence *The figure is a rear elevation of a top for powder-receptacles, showing my new design* inserted instead; and that the said Letters Patents should be read with this correction therein that the same may conform to the record of the case in the Patent Office.

Signed and sealed this 20th day of November, A. D., 1906.

[SEAL.]

F. I. ALLEN,
Commissioner of Patents.
